(57) **CLAIM**

The ornamental design for a gaming system volatility marker, as shown and described herein.

DESCRIPTION

FIG. 1 is a perspective view of one embodiment of the gaming system volatility marker of our new design.

FIG. 2 is a front view of the gaming system volatility marker of FIG. 1.

FIG. 3 is a perspective view of another embodiment of the gaming system volatility marker of our new design; and, FIG. 4 is a front view of the gaming system volatility marker of FIG. 3.

Those portions shown in phantom are for environmental purposes only.

1 Claim, 4 Drawing Sheets(56)
